FILLING MACHINES

Jerry A. Krizka, Chicago, Ill., assignor to Pak'tronic
Machine Corporation, a corporation of Ohio
Filed Nov. 9, 1961, Ser. No. 151,335
15 Claims. (Cl. 141—141)

This invention relates to a novel and improved filling head for filling semi-liquid bulk materials, such as ice cream, into open containers, and also relates to a novel and cooperating machine for introducing the filling head into the container, following the filling head as it rises in the container, and abruptly breaking the filling head clear of the top of the container in a manner which cleanly separates the semi-liquid in the container from that extruded from the head.

It is a principal object of the present invention to provide a novel filling head and cooperating machine which can be used for filling containers which are intermittently placed under the filling head while at the same time being fed continuously by a standard continuous ice cream making machine.

It is another major object of the present invention to provide an improved filling head and machine which fills containers at a very high rate while at the same time completely avoiding smearing or contaminating of the closure seal surfaces around the perimeter of the container with the ice cream being extruded thereinto.

Still a further object of the invention is to provide a filling head structure which is quickly and easily detached from a supporting plate, forming part of the filling machine and which can be quickly knocked down into its several components without use of tools so that it may be fully cleaned and sterilized and then reassembled with a minimum of effort.

It is a further object of major importance to provide a filling head having an extrusion orifice defined by a novel grating having a series of apertures so located and so vented to the atmosphere that when the head is abruptly retracted upwardly out of the container, the ice cream breaks into a plurality of low pyramid-type peaks, and breaks in such a manner that the ice cream is not splattered or drawn upwardly into long thin wisps, whereby a clean break is accomplished.

Another object of the invention is to provide an improved machine which cooperates with means for advancing the containers to lower the head into each container the instant that it arrives thereunder, follows the rise of the head as the head is floated upwardly in a container by the extrusion of ice cream thereinto, and then suddenly snaps the head upwardly out of the container to affect a clean break between the ice cream left in the container and the ice cream in the filling head. The container-advancing means then moves the filled container out of the way and places an empty container under the head which is then immediately lowered into the new container to begin filling the latter. The containers are changed under the head so quickly that the ice cream continuously fed to the head does not have time to drop therefrom during the change.

It is another object of this invention to provide a novel electrical control means cooperating with the container-advancing means and the filling head means to completely control the motions of the machine and the head, certain motions of the sequence of operation being initiated by the advancing of a container, and other motions being initiated by the filling of ice cream to a predetermined level. One function of the control means is to cause the head drive mechanism to closely follow the motion of the filling head as it is floated upwardly in the container without affecting this action until a desired level of ice cream has been filled into each container, whereupon the machine

2

abruptly snaps the head out of the filled container, and the control means advances a container thereunder. An adjacent mechanism, which forms no part of the present invention, closes the open end of each filled container in one of a plurality of suitable manners.

5 Other objects and advantages of the invention will become apparent during the following discussion of the drawing, wherein:

10 FIG. 1 is an end elevation view of the filling head and machine operatively associated with a conveyor along which the containers are advanced;

15 FIG. 2 is a side elevation of the machine of FIG. 1 but showing the mechanism in a later position advancing the filling head into the container;

20 FIG. 3 is a simplified view similar to FIG. 2 but showing the filling head down in the container and floating therein on the ice cream;

25 FIG. 4 is a view similar to FIG. 3 but showing the mechanism in a still further advanced position with the ice cream filled nearly to the top of the container;

30 FIG. 5 is a view similar to FIG. 4 but showing the mechanism in a still more advanced position in which the filling head has been broken free of the ice cream in the filling container;

35 FIG. 6 is a schematic diagram showing a suitable electrical control circuit for use with the present mechanism;

FIG. 7 is a side elevation of the filling head;

FIG. 8 is an end elevation of the filling head;

30 FIG. 9 is a perspective view showing the bottom of the filling head;

35 FIG. 10 is a detail view of the grating and vent tubes of the filling head;

40 FIG. 11 is an end view of the grating and vent tubes shown in FIG. 10;

45 FIG. 12 is a plan view of the filling head shown in FIG. 8, and showing the mounting ring attached thereto;

50 FIG. 13 is a view similar to FIG. 12 but showing the mounting ring removed;

55 FIG. 14 is a detailed view of the mounting ring;

FIGS. 15, 16 and 17 are elevation views showing the filling head in three successive positions with respect to a carton being filled, FIG. 15 showing the filling head above the carton and being lowered thereinto, FIG. 16 showing the filling head inside the carton and floating upwardly on the ice cream therein; and FIG. 17 showing the filling head after having just broken clear of the top of the carton.

Referring now to the drawings, FIG. 1 shows an ice cream filling machine mounted on a stationary platform 1 and including two upright supporting rods 2 rigidly fixed in the platform 1. The platform also supports a motor M driving an electric clutch 3 which in turn drives a gear reducer R having a shaft extending outwardly just beyond the two upright rods 2. An arm 5 is attached to and rotates with this shaft and drives a connecting link 6 up and down in a well known manner. The upper end of the link 6 is connected with a first sliding block 7 which is journaled to slide up and down on the upright rods 2. Above the block 7 is an upper block 8 which supports a horizontally disposed plate 9 carrying at its outer end an ice cream filling head 20, the latter being discussed in greater detail in connection with FIGS. 7 through 17, inclusive. The plate 9 has two downward extensions 10 and 11, FIG. 1. The downward extension 11 comprises a control rod which extends into a plunger-type potentiometer P which is mounted on the lower bearing block 7 and slides up and down therewith. Ordinarily, the upper bearing block 8 is supported by resting upon the block 7 and therefore there is no relative motion therebetween. However, when the blocks 8 and 7 separate in a manner to be hereinafter described, the resistance of the potentiometer P is changed by the sliding of

the rod 11 out of the potentiometer P, thereby varying the resistance of the potentiometer in the manner shown schematically in FIG. 6. The other downward extension 10 supports two small pawls 12 and 13, these pawls being pivotally connected to the extension 10 as can best be seen in FIG. 1. The upper pawl 12 at its right end actuates a switch X2 and at its left end carries a weight which maintains the pawl 12 normally in a horizontal position by resting on a lug 10a which forms a part of the downward extension 10. The pawl 13 near the bottom of the downward extension 10 normally rests upon a lug 10b which maintains this lug horizontal but permits it to yield in order to pass the switches X2 and X3 when it is traveling downwardly, but so that it throws both switches upwardly into the "on" position when it is rising therewith. The upper switch X3 is a spring-urged, normally open switch which is only momentarily closed by the passage of the pawl 13 therewith when the latter is moving in an upward direction as will be hereinafter explained in greater detail.

The ice cream filling head 20 is disposed above an empty container C which is located on the belt B of a moving conveyor means which per se forms no part of the present invention. The belt B is merely shown to assist in illustrating the cooperation between the switch X3 and a container-advancing means comprising a hook H, FIG. 2, which is moved rightwardly against the restraining action of a spring L by a solenoid S when the latter is energized, this illustrative arrangement providing means for advancing the belt B through the width of a container C once during each cycle of the machine in order to place an empty carton under the filling head and to move a filled carton therewith. As stated above, the belt and the other specific features of the container advancing mechanism form no part of the present invention and are merely included to show a complete operative embodiment. By referring to the wiring diagram of FIG. 6, it will be seen that when power is applied at the plug D the motor M runs continuously. This motor is coupled through the electric clutch 3 with the gear reduction R so that the gear reduction is driven to the extent that the clutch 3 is energized. When this clutch is fully energized, the drive from the motor to the reduction gearing R is firmly established, but when a resistance such as that of the potentiometer P is introduced in series with the power line to the clutch 3, the clutch does not positively drive the reduction gearing but allows it to slip to a certain extent, the positiveness of the drive being determined by the amount of current allowed to flow through the clutch 3 and the potentiometer P when the switch X2 is open. The current to the clutch is fully interrupted whenever the switch X1 is open, and by referring to FIGS. 1 and 6 it can be seen that this switch is normally open, but is closed by the presence of a container C to be filled beneath the filling head 20. Thus, if no container is there, clutch 3 is fully disengaged. When a container C actuates the switch X1, the circuit is closed to deliver power both to the potentiometer P and to the switch X2. When the switch X2 is closed as shown in FIG. 6, full current is delivered directly to the clutch 3 regardless of the position of the potentiometer P. However, if the switch X2 is open the resistance of the potentiometer P, which is a function of the amount of separation between the bearing blocks 7 and 8, determines the amount of current which can flow to the clutch 3, and thereby determines the degree of coupling of the motor to the gear reduction unit R. Switch X3 is a normally open switch, but when closed remains closed only so long as its toggle arm is held in closed position by the pawl 13. Upon release of the toggle arm, the switch X3 immediately opens. This switch is connected directly to the solenoid S which is used to advance the belt by engagement of its hooked end H into an opening B' in the belt B. When the solenoid S is energized, the hooked end H is thrown upwardly by a small station-

ary wedge so that it engages the hole B', which is one of a plurality of holes spaced along the belt with separations therebetween approximating the width of the container C. FIG. 1 shows the machine with its filling head in its upmost position, and FIGS. 2, 3, 4 and 5 show it in progressively later positions.

The operation of the machine is as follows: When a container C is brought by the belt B into alignment beneath the filling head 20, the switch X1 is thereby closed and the clutch 3 is fully energized so as to tightly couple the motor to the reduction unit R and thereby drive the shaft at a predetermined rate in the counterclockwise direction, as shown in FIG. 2. The arm 5 rotates downwardly from its uppermost position as shown in FIG. 1 and pulls the link 6 downwardly therewith, thereby lowering the block 7 to the position that it occupies as illustrated in FIG. 3. The bearing block 8 follows the block 7 down until the ice cream filling head 20 has entered the container C and has gone downwardly therewith as far as it can go due to floating on the ice cream. As was stated above, the filling head is connected with a continuous ice cream making machine. Ice cream is pumped at a continuous rate into and through the head 20. Thus, only a little of the ice cream I is shown emerging from the head in FIG. 1, whereas in FIG. 2 and in FIG. 15 a much larger amount of ice cream has extruded from the head and is hanging generally toward the container therebelow. As the filling head 20 is lowered into this container, ice cream is distributed therein and fills the bottom of the container and floats the head thereon. At this point, the head can travel downwardly no further, as shown in FIG. 3, and therefore the lower block 7 retreats downwardly away from the upper block 8, which it previously supported. The pawl 13 has passed both switches X2 and X3 in its downward motion without actuating either of these switches, but at this point the pawl 12 reaches the toggle arm of the switch X2 and throws this switch downwardly to its "off" position. By inspection of the wiring diagram of FIG. 6 it will be seen that when switch X2 is opened so that control of the amount of current through the clutch 3 then becomes solely dependent upon the position of the control rod 11 in the potentiometer P. Since the control rod 11 is connected by the plate 9 directly with the upper bearing block 8 and since the barrel of the potentiometer P is directly carried by the lower bearing block 7, it will be seen that the rod 11 has been pulled outwardly of this potentiometer in FIGS. 3 and 4, which is the direction which decreases the amount of resistance placed in the circuit by the potentiometer P, and the amount of coupling provided by the electric clutch 3 increases. Thus, the clutch continues to turn the reduction gearing so that the arm 5 passes through bottom dead center and heads back up again towards the upper bearing plate 8.

It is intended in this portion of the cycle that the block 7 closely follow the block 8, but that it does not push this block upwardly while the ice cream is filling the container, as shown in FIGS. 3 and 4. Thus, as the block 7 begins to catch up with the block 8, FIG. 4, the control rod 11 is pushed further into the barrel of the potentiometer P and increases its resistance, thereby decreasing the amount of current flowing through the electric clutch and permitting the latter to slip to a greater extent. This potentiometer P is so adjusted that the block 7 almost comes in contact with the block 8 but doesn't quite fully contact it. It merely follows the block 8 upwardly, the latter being floated and raised by the ice cream which is forced through the filling head 20 to fill the container.

Finally, when the ice cream has reached a predetermined level in the container and has almost filled it, the pawl 13 rises to the toggle arm on the switch X2 and throws this switch to its "on" position, in which position it remains during the rest of the cycle. The instant the switch X2 is closed, full power is applied to the clutch 3

and the coupling becomes tight between the motor M and the reduction gear R and drives the bearing block 7 upwardly so that it strikes the bearing block 8, and abruptly drives it upwardly, thereby suddenly snapping the filling head out of the container C.

The switch X3 is so placed above the switch X2 that at the moment the filling head just clears the top of the container C, the pawl 13 contacts the toggle arm of the switch X3 and moves it into its closed position. This motion energizes the solenoid S which then engages the hook H in the hole B' in the belt and moves the belt to the right in order to take away the filled container and place an empty container beneath the filling head 20. The instant the pawl 13 has passed the switch X3, this switch returns to its normal open position, which de-energizes the solenoid S and permits the hook H to be returned by the action of the spring L to its relaxed position as shown in FIG. 2. A full cycle is then completed and commences all over again as soon as the switch X1 is reclosed by the presence of a container C in contact therewith, this switch being also of the normally open variety.

The filling head

As pointed out in the objects of this invention, one of the most important objects of the present invention is to provide a filling head which can be operated by a machine to fill containers at such a high rate of speed that the ice cream from a continuous ice cream maker (not shown) can be continuously pumped to the head. This type of operation not only requires a very high speed machine, but in addition it requires special features of the ice cream filling head which will permit this head to be abruptly retracted out of a container when the container has reached the proper filling level without splattering ice cream or pulling it out into long thin wisps which may then bend over and wet the perimeter of the container. The present machine is especially intended for use in connection with automatic carton-making and -closing machinery, and especially it is the intention that the closing step be carried out by a heat-sealing process. This heat-sealing process cannot be successfully used to seal the container if the container is wetted by ice cream spilled thereon during or after the filling process. The ice cream filling head which has been developed through experimentation to meet the above practical requirements is illustrated in FIGS. 7 through 17 of the drawings.

The filling head in general is designated by the reference numeral 20 and comprises a rectangular body portion designed to be a relatively snug fit in the ice cream containers C which it is to fill. The body has an open lower end comprising an extrusion orifice and has an upper end which tapers into a pipe 21 through which the ice cream is pumped by a pump 19 from a continuous ice cream making source, FIG. 1. Between the pipe 21 and the body of the filling head 20 is a boss 22, FIG. 7, which is solid, as distinguished from hollow so that no pockets will be present which can collect food. This boss has three openings therethrough as can be seen in FIG. 7, including the central opening which connects with the pipe 21 and two smaller openings 23 adapted to receive the tubes 24 shown in FIGS. 10 and 11 for the purpose hereinafter stated. Note that the upper end of each of the tubes 24 has an enlarged ring 25 integrally attached thereto, and that the diameter of the ring is such as will just pass through the small bores 23. The tubes 24, FIGS. 10 and 11, extend downwardly and are fixed at their lower ends in a grating 26 which has a step in its outside periphery so that it can be inserted up into the body of the head 20 so as to mate therewith flush with the outside surface thereof, as shown in FIG. 7. The lower periphery of the grating 26 is chamfered as at 26a so that it can be guided easily into an ice cream container. The grating has eight apertures or windows W through which the ice cream emerges and flows into the container C. The tubes 24 extend through

the grating to the points marked 24' in FIG. 9, and these tubes register with a groove 27 which extends substantially across the width of the grating 26. The tubes 24 thereby vent the groove 27 to the atmosphere at the top of the filling head in the vicinity of the rings 25 so that when the filling head is abruptly retracted away from the ice cream and out of the filled container, no vacuum will be developed which will tend to prevent a clean break between the ice cream in the container C and the ice cream in the filling head 20.

10 The tubes 24 and the rings 25, however, serve still another purpose by providing a quick-detach type mounting of the filling head on its supporting plate 9, employing a collar 28 which can be seen in detail in FIG. 14 to hold the filling head on the plate. The plate 9 has an opening there-through sufficient to pass the ice cream pipe 21 and the tubes 24 including the rings 25 at the upper ends thereof. The collar 28 has two slotted holes 29 therethrough, one end of each hole being of diameter sufficient to pass the rings 25, the slot itself being only as wide as the outer diameter of the tubes 24. By this means the filling head can be passed through a mounting hole in the plate 9 and the collar can be slipped down over the ice cream pipe 21 and the retaining rings 25 and then rotated in the manner shown in FIG. 12 so as to turn the holes and slots 29 in 15 such a direction as will retain the filling head 20 tightly engaged with the plate 9. This structure provides a quick-disconnect means permitting not only the removal of the entire assembly of the filling head 20 from the plate 9, but at the same time releases the grating and the tubes 24 20 from the body of the filling head 20 so that these members, as shown in FIGS. 10 and 11, can be disassembled therefrom. This type of structure has been approved as satisfactory for use in connection with the filling of ice cream containers, in view of the fact that this head can be quickly 25 disassembled and sterilized. In the production model of the head, all parts thereof, including the grating, are made of stainless steel so that none of the parts will be damaged by sterilization.

FIGS. 15, 16 and 17 are included to illustrate in greater 30 detail the manner in which the ice cream head first enters the container C with the ice cream I extruding from the head and already hanging considerably below the grating 26. By the time it reaches the bottom of the container, the ice cream is almost ready to fall free of the head, but 35 the timing and the ice cream temperature are such as to prevent undesired dropping.

The container then is filled as shown in FIG. 16 by having the head 20 actually floated on top of the ice cream being extruded therefrom into the container. Finally, 40 the machine abruptly retracts the filling head 20 upwardly 50 away from the container C and breaks the ice cream into a plurality of little pyramids in the container C, which pyramids are quickly and easily flattened when the end closure is applied to the container and sealed thereto by 55 a machine (not shown) in a subsequent operation, which operation is not illustrated because it forms no part of the present invention.

The cross-sectional dimension of the ice cream container actually being filled by the present machine is about 60 3 1/4 x 4 1/4 and the eight windows W in the bottom of the grating 26 permit the rapid flow of ice cream into the container C, but on the other hand provide sufficient restriction of the orifice of the ice cream filling head that when 65 the head is suddenly and rapidly retracted away from the container C the ice cream peaks which form as small pyramids on the top of the container are only about 1/2" high, and these peaks break in a completely clean and satisfactory manner with the peaks which remain at the bottom of the ice cream filling head as it rises away from the container.

I do not limit my invention to the exact forms shown in the drawings or to the precise use recited for illustrative purposes, for obviously changes may be made therein 70 75 within the scope of the following claims.

I claim:

1. A machine for automatically filling containers with a semiliquid material supplied by a source, comprising a filling head shaped to fit inside a container; conveyor means for intermittently advancing said containers under said filling head; pump means between said source and said head to force the material through the head and float the head upwardly thereon within the containers; reciprocating head-support means above said conveyor means; first control means at the conveyor means and actuated by the advance of a container under the head; second control means responsive to the floating of the head to a predetermined level; and reciprocating drive means engaging said head-support means to lower the head into a container in response to the actuation of the first control means by the advancing of a container under the head, and said drive means including means responsive to the second control means to abruptly raise the head-support means away from the container.

2. In a machine as set forth in claim 1, said filling head fitting snugly in the containers and having an orifice through a face disposed transversely of the axis of reciprocation of the filling head through which said material extrudes, the area of the orifice being smaller than the area of the transverse face.

3. In a machine as set forth in claim 1, said drive means comprising a motor; a block reciprocably mounted below said head-support means; translatory means for translating rotary motion of the motor to reciprocatory motion of the block; slip clutch means coupling the motor to the translatory means; said first control means including sensor means responsive to the placing of a container below the head for engaging the clutch means to lower the block and the head-support means resting thereon; sensor means to disengage the clutch when the block reaches the bottom of its reciprocation; sensor means sensitive to the spacing between the block and the support means and partially engaging the clutch means to make the block follow the support means upwardly; and said second control means including sensor means responsive to the arrival of the head-support means at said level to fully engage the clutch.

4. In a machine as set forth in claim 3, means responsive to the raising of the head out of the container to advance said conveyor means.

5. A machine for automatically filling containers with a semiliquid material supplied by a source, comprising a filling head shaped to fit inside a container; conveyor means for intermittently advancing said containers under said filling head; pump means between said source and said head to force the material through the head and float the head upwardly thereon within the container; reciprocating head-support means above said conveyor means; reciprocating drive means below and supporting said head-support means; and drive control means responsive to the advancing of a container under the head for lowering the head thereinto, responsive to the spacing between the head-support means and the drive means to make the latter follow the upward floating of the former, and responsive to the arrival of the head at a predetermined level to abruptly raise the head-support means away from the container.

6. In a machine as set forth in claim 5, said drive means comprising a motor; a block reciprocably mounted below said head-support means; translatory means for translating rotary motion of the motor to reciprocatory motion of the block; an electric clutch coupling the motor to the translatory means; and said control means comprising a first switch responsive to the placing of a container under the head for energizing the clutch to lower the block and the support means resting thereon; a second switch for deenergizing the clutch when the block reaches the bottom of its reciprocation; potentiometer means connected between the block and the support means and having a resistance inversely proportional to the spacing

therebetween for partially energizing the clutch to make the block closely follow the support means upwardly; and a third switch responsive to the arrival of the support means at said level to fully energize the clutch.

5. In a machine as set forth in claim 6, means responsive to the raising of the head out of the container to advance said conveyor means.

8. In a machine as set forth in claim 6, said translatory means comprising a reduction gear driven by the motor and driving a crank arm, and a connecting rod coupling the crank arm with the block.

10. In a machine as set forth in claim 6, said translatory means comprising a reduction gear driven by the motor and driving a crank arm, and a connecting rod coupling the crank arm with the block.

15. A machine for automatically filling containers with a semiliquid material pumped thereto at a continuous rate from a source, comprising a filling head coupled to said source and shaped to fit inside a container; means for advancing containers opposite said head; head-support means for reciprocating said head toward and away from said containers; and head-support drive means responsive to the placing of a container opposite the head for

20. advancing the latter thereinto, the continuous flow of material forcing the head back outwardly of the container; control means responsive to the position of the head when the container has been filled to a predetermined level, and said head support drive means including means to abruptly retract the head away from the container and break the flow of material thereto in response to actuation of said control means.

25. In a machine as set forth in claim 9, said filling head fitting snugly in the containers and having an orifice through which the material extrudes and located in a face disposed transversely of the axis of reciprocation of the filling head, the area of the orifice being smaller than the area of the transverse face.

30. 10. In a machine as set forth in claim 9, said filling head fitting snugly in the containers and having an orifice through which the material extrudes and located in a face disposed transversely of the axis of reciprocation of the filling head, the area of the orifice being smaller than the area of the transverse face.

35. 11. In a machine as set forth in claim 9, a grating across said orifice and dividing it into a plurality of smaller openings, and vent tube means extending from outside the head to points in the vicinity of the grating to admit air when the head is retracted away from the container.

40. 12. In a machine as set forth in claim 11, said semiliquid material comprising a food product, and said grating and vent tube structure being disassemblable from the head to facilitate cleaning and sterilizing of all of the parts.

45. 13. In a machine as set forth in claim 9, said filling head having a neck extending through an opening in said head-support means; and a collar having a twist-lock engagement on said neck for retaining the head on the support means by a quick-disconnect type joint.

50. 14. A machine for automatically filling containers with a semiliquid material pumped thereto at a continuous rate from a source, comprising a filling head coupled to said source and shaped to fit down inside a container; intermittent means for advancing containers one at a time under said head; head-support means for reciprocating said head toward and away from said containers; head-support drive means responsive to the placing of a container under the head for lowering the latter thereinto, the continuous flow of material forcing the head to rise upwardly in the container; means responsive to the position of the head when the container has been filled to a predetermined level; and said head-support drive means including means to abruptly retract the head out of the container and break the flow of material thereto; and means responsive to the raising of the head from the container to advance said intermittent means.

55. 60. 65. 15. In a machine as set forth in claim 14, said drive means comprising a motor; a block reciprocably mounted below said head-support means; translatory means for translating rotary motion of the motor to reciprocatory motion of the block; slip clutch means coupling the motor to the translatory means; sensor means responsive to the placing of a container below the head for engaging the clutch means to lower the block and the head-support means resting thereon; sensor means to disengage the clutch when the block reaches the bottom of its reciprocation.

70. 75. 75.

cation; sensor means sensitive to the spacing between the block and the support means and partially engaging the clutch means to make the block follow the support means upwardly; and sensor means responsive to the arrival of the head-support means at said level to fully engage the 5 clutch.
